UNITED STATES PATENT OFFICE.

ARTHUR E. PETERS, OF WESTMONT BOROUGH, PENNSYLVANIA.

COKE-OVEN.

1,183,401.

Specification of Letters Patent. Patented May 16, 1916.

Application filed September 10, 1913. Serial No. 789,052.

To all whom it may concern:

Be it known that I, ARTHUR E. PETERS, a citizen of the United States, residing in the borough of Westmont, in the county of 5 Cambria and State of Pennsylvania, have invented certain new and useful Improvements in Coke-Ovens; and I do hereby declare the following to be a full, clear, and exact description of the invention, such as will enable others skilled in the art to which it appertains to make and use the same.

My invention relates to coke ovens of the retort type and among the objects thereof are the following:—The construction of the 15 brick work in a simple manner allowing ease of inspection, repair and maintenance. The simplicity of the upper and superimposed portions of the construction, as the only parts which are on top of the ovens are 20 the tracks for the charging lorry, gas collecting mains and uptakes, and, of course, the filling holes for charging the coal in the ovens, and covers thereof. It must be noted that the upper portion of my ovens is 25 simple and does not have many usual constructions such as inspection holes, burner pipes, apparatus for adjusting and regulating the flow of air and gas, etc.

Another object of my invention is to so 30 construct the ovens that the tops are provided with cooling flues which may be connected to an exhaust or pressure fan or blower, to keep the upper portion comparatively cool.

35 Another, and one of the principal objects of my invention, is to so arrange and construct the ovens that the path of the burning gas through the heating flues of the same is always in the same direction through 40 the vertical flues between adjacent ovens, so that after the air dampers and burners are once adjusted this adjustment will not be changed nor modified by carbon deposition nor by the destructive melting or fluxing of 45 the material forming the gas or air channels or connections by the heat of the effluent gases, which latter effect is quite customary in ovens wherein the directions of the flow of the gases through these flues is 50 reversed from time to time.

Another object of my invention is to so 55 construct the two principal flues, that is one for hot air and one for effluent or off-gases, in such a way that they extend longitudinally of the battery of ovens with branch flues from the same to the heating flues of

the oven, and the construction and arrangement of these flues is such that the hot air flue is used only for hot air and the off-gas flue only for off-gas. To this end, I provide 60 a regenerator, a stack and a fan or blower at each end of the battery of ovens, all which are so arranged that the path of the off-gas and of the air from the regenerator to the stack is of the same length, and consequently 65 subject to the same frictional resistance through any one, or all the ovens.

Another object is to so construct and arrange the burners and the air regulating dampers that they are adjusted from below 70 the ovens, the result of which is that any brick dust, spawls, ash or other accumulation will fall out by gravity when the damper or the burner is removed.

Another object of my invention is to so 75 arrange the gas flues and air flues that one branch of each of these will serve two ovens.

Another object is to so construct and arrange the burner openings and other openings below and in line with the vertical flues 80 so that the heat and condition of the heating flues may be readily inspected by an attendant who can by removing the burner or plug look directly upward into said flues, protecting his eyes meanwhile, if necessary, by 85 goggles or large spectacles.

Having thus given a general description of my invention, I will now refer to the accompanying three sheets of drawings which form part of this specification, and in which 90 like figures and characters refer to like parts.

Figure 1 is a vertical longitudinal sectional elevation of one of my ovens, the plane of said section being transverse of the 95 battery in general, this section being taken on the line I—I of Fig. 4. Fig. 2 is a horizontal sectional plan taken on the line II—II of Fig. 1. Fig. 3 is a horizontal sectional plan taken on the line III—III of Fig. 1. Fig. 4 is a vertical transverse sectional elevation taken on the line IV—IV of Fig. 1. Fig. 5 is a diagrammatic plan of a battery of my coke ovens broken in the middle for the sake of clearness of illustration, showing the arrangement of air valves, regenerators, main flues, and branches. Fig. 6 is a diagrammatic isometric projection of flues and connections of a battery of my ovens showing the flues, regenerators, stacks, and 105 blower, with the air currents flowing in one direction as indicated by the arrows. Fig.

7 is a diagrammatic isometric projection similar to Fig. 6, the only difference being that the air currents are flowing in reverse directions. Fig. 8 is a vertical longitudinal sectional elevation on an enlarged scale through the gas burner and individual damper and sight opening in the lower part of my ovens taken on the zig-zag line VIII-VIII of Fig. 3.

10 Referring now to the characters of reference on the drawings: The battery of coke ovens in general is indicated as 1, the retort portion of each individual oven is indicated as 2, the heating flues which are of inverted U form, are indicated as 3 while 4 are the upper connecting channels between the adjoining portions of the pairs of vertical heating flues 3—3 and 5 is the central division wall of refractory material between said vertical flues.

15 6 are the gas ports whereby the gases enter one of each pair of the vertical flues 3—3 and below the same are the mixing chambers 7—7 in the lower part of which the gas burner opening 8 is provided. Into each of the gas burner openings 8, the burner pipe 9 is inserted and provided with regulating valves 49 and connected with the branch gas pipe 10, which in turn is connected to the 20 gas main 11, which extends longitudinally under the battery of ovens as shown.

25 As indicated in Figs. 5, 6, and 7, fans or blowers are indicated as 12 and 13, one of which is at each end of the battery and 30 adapted to receive atmospheric air directly or from the ducts 42 and discharge the same under pressure. The air flues 16 and 17 lead to the regenerators 18 and 19; reversing valves between the blowers, the chimneys 35 and the regenerators are indicated as 14 and 15, while 20 and 21 represent other reversing valves between the regenerators and the air and the off-gas flues adapted to control or 40 direct the flow of air through these, either in one direction or the other.

45 As may be seen particularly on reference to Fig. 5, 23 is the main hot air flue which extends along one side of the battery as shown, and 22 is the main off-gas flue which 50 extends along the other side of the battery. Flues or pipes 24 and 25 extend from the valves 14 and 15 to the chimneys or stacks 26 and 27 respectively, and are adapted to connect the regenerators 18 and 19 with said 55 stacks.

55 The horizontal longitudinal off-gas flues of the coke ovens are indicated as 28 from which a number of ports 30 are connected at intervals, as shown, each of said ports leading from an off-gas chamber 31 to said flue 28, which off-gas chambers are located below the discharging one of the pair of heating flues 3, being connected thereto by the off-gas ports 30.

60 65 The horizontal longitudinal hot-air flues

of the coke ovens are indicated as 29 from which ports 32 lead at intervals to the mixing chamber 7 thence to the entering one of the pair of vertical heating flues 3 through the ports of openings 6, as shown.

70 In order that the operation of the front and rear of the ovens may be symmetrical, the heating flues 3 in the front half of the oven are oppositely disposed from those in the rear half of the oven. The products of combustion will therefore flow continually toward the center of the oven in the upper connecting chamber 4.

75 Chambers 31 are formed as shown below one leg of each pair of vertical flues 3, and 80 at the bottom of each is provided a vertical inspection opening 33. This inspection opening is closed by a metal or refractory plug 34 maintained in position by a screw 36, which in turn is supported by the swinging stirrup 35. This stirrup may be swung on its pivots, shown in Fig. 8, so as to be out of the way when the plug 34 is taken out of or placed in the bottom of inspection hole 33. Regulating ports 32 are formed between 85 the hot air flue 29 and the mixing chamber 7 as shown in detail in Fig. 8, the cross-sectional area of the regulating port 32 being capable of adjustment by the up or down movement of the damper 38 which operates in the openings 39. This damper 38 is composed of a plurality of refractory blocks as shown, superimposed one upon another and capable of up and down movement and adjustment by means of a screw 41, which 90 screw is supported by the swinging stirrup 40 which is pivoted in a manner similar to that described in connection with the swinging stirrup 35. This damper is a simple and yet efficient construction in that it is composed of a number of pieces of refractory material or bricks which merely rest by their own weight on the adjusting screw 41, so that gravity will lower them as the screw is moved downward and it may be moved upwardly by a reverse motion of said screw. When it is desired to remove the damper, the bricks or pieces thereof can be taken out one by one, and replaced by reverse operation.

95 By making the damper in sections, each of which is merely superimposed on the one below, it is a simple construction, but at the same time economical and efficient, in that no metal parts are exposed to the heat and no large refractory pieces are required, which larger pieces would be fractured in use. The cooling ducts in the upper portion of the oven are indicated as 42, the lorry track on top of the ovens is indicated as 43, the gas collecting branch pipes from each oven are indicated as 44, and the gas collecting main as 45.

100 I have shown the battery of ovens supported on girders 46 which have their ends resting on the outer foundation walls, the

center of each girder being further supported by means of posts or columns 47. An open space 48 extends under the entire battery of sufficient height to allow the attendants to inspect the heating flues 3 or to regulate the burner valves 49 or the dampers 38 as required.

The air ducts 42 may be connected with the atmosphere at one end and may have 10 a draft stack at the other end to insure passage of cooling air therethrough, or the cooling air may be forced through the ducts by a fan or blower, or the air to supply the fans 12 and 13 may be drawn by said fans 15 from and through said ducts 42 which will then furnish warm air to the fans, thereby conduced to economy.

The valves 14, 15, 20, and 21 are shown in Figs. 6 and 7 in a diagrammatic manner, 20 the longer straight lines indicating that the passage or flue represented by said lines is open in the direction of the line, while the short lines perpendicular to and between the ends of the longer lines indicate that the 25 valve is turned and the passage or flue closed thereby at that place.

The charging openings through which coal is put into the ovens are indicated as 37. The illustrations of my oven do not 30 show the end doors, but these may be supplied in the customary form of construction.

The operation of my coke oven is as follows:—From time to time bituminous coal is charged into one or more of the ovens 35 while similar charges in other ovens are being coked. As the charges in various ovens forming a battery or a number of batteries are in different conditions, some of the coal being green, other ovens filled with coal that 40 is partially coked, still others with coke that is practically finished, this gives a fairly constant amount of distillate gas supply which is gathered in the collecting main 45 and delivered thence into a regulator or gas holder which supplies the gas main 11 with gaseous fuel obtained from the coking operation. This gaseous fuel is introduced through the burner pipes 9 and regulated 45 by the burner valves 49 in such a way that 50 the temperature throughout the length of the oven is reasonably uniform, and in general I find that more gas is needed toward the ends of the ovens where the radiation is greater than near the center or intermediate 55 portions thereof and I regulate the supply accordingly.

A distinctive feature of my construction is due to the fact that the gaseous fuel discharged from the burner pipes 9 issues into 60 the vertical heating flues 3 and always travels through these vertical flues in the same directions as indicated by the arrows in Fig. 1.

In order to take advantage of the heat of 65 the escaping gases, I provide regenerators as

heretofore described which are used alternately for the purpose of heating the air which is supplied for the combustion of the heating gas. As indicated in Fig. 5 of the drawings, the blower 12 is in operation, taking atmospheric air at ordinary temperature and discharging it through the pipe 16 to the regenerator 18 which is provided with brick loosely set therein and with a central division wall extending to a short distance from 70 the top as indicated in Figs. 5, 6, and 7. This regenerator has been previously heated by the passage of the products of combustion therethrough, so that it is now in a condition to heat the atmospheric air which passes 80 through it. As shown in Fig. 5 the reversing valve 20 is set, so that the hot air passes through the hot air flue 23 and thence to the horizontal hot air flues of the coke ovens indicated as 29, thence through the ports 85 32 into the mixing chambers 7 in which it meets the gaseous fuel which is discharged into the mixing chambers 7 through the openings 8 connecting with the burner pipes 9. From the mixing chambers 7 the mixture 90 of burning gas and air issues into one of each of the pair of legs 3 of the vertical heating flues, passes upwardly through the same, traverses the horizontal portion 4 and then down the other leg of the heating flue 95 3, thence through the off-gas ports 50 into the off-gas chambers 31, then through the off-gas ports 30 into the horizontal longitudinal off-gas flues 28 thence to the main off-gas flue 22, thence through the valve 21 100 into the regenerator 19, which the off-gases heat in passing, thence passes the valve 15 into the pipe 25 and to the stack 27 where the spent gases are discharged into the atmosphere.

The reversal of the valves at the proper times will change the direction of the hot air and the off-gases in their respective flues and channels while at the same time the heating gases and the course of the same 110 through the ovens is maintained without reversal. In order to regulate the amount of air which is directed into each of the heating flues 3—3 the damper 38 may be moved up and down as desired by the hand-wheel 41. When, however, each of these dampers 38 is so set as to provide a proper amount of air to each pair of heating flues in order to maintain a uniform temperature throughout the length of the oven, these 115 dampers need not thereafter be changed as the same conditions will continue to exist if nothing unusual should occur.

In order to inspect the chambers and heating flues the plugs 34 may be withdrawn and 12 the temperature estimated by the eye of the attendant or by a pyrometer introduced through the opening 33 as may be expedient or necessary.

In order to clearly show the course of the 13

air, the burning gas and the off-gases, I have illustrated this diagrammatically in Figs. 6 and 7 of the drawings.

In Fig. 6 the atmospheric air is drawn in by the fan or blower 13, discharged through the pipe 17, past the valve 15 into the regenerator 19 where it is heated, thence past the valve 21 through the main hot air flue 23, thence through the horizontal longitudinal hot air flues 29, thence through the regulating ports 32 into the mixing chambers 7 connecting therewith, where the air mixes and begins to burn with the fuel gas, thence through the ports 6 into the updraft legs 3 of the vertical heating flues, thence through the upper connecting channels 4 then downwardly through the down-draft legs 3 of the vertical heating flues, thence through the off-gas ports 50 into the off-gas chambers 31, thence through the ports 30 into the horizontal longitudinal off-gas flues 28 of the coke ovens, thence through the main off-gas flue 22 past the valve 20, thence into the regenerator 18, which the off-gases heat in traversing, thence past the valve 14 into the pipe 24 and thence into the stack 26, whence the off-gases are discharged into the atmospheric air.

As shown in the diagram of Fig. 7 the regenerators, hot-air flues and off-gas flues are working in a reverse manner, namely:— The atmospheric air is drawn in by the fan or blower 12 thence into the pipe 16 past the valve 14 into the regenerator 18 where said air is heated, thence past the valve 20 into the main hot air flue 23, thence into the horizontal longitudinal hot air flues 29 of the coke ovens, thence through the regulating ports 32 into the mixing chambers 7, where the air mixes and begins to burn with the fuel gas, thence through the ports 6 into the up-draft leg of the vertical heating flues 3 thence through the connecting channels 4 into the down-draft legs of the vertical heating flues 3, thence through the off-gas ports 50 into the off-gas chambers 31, thence through the ports 30 into the horizontal longitudinal off-gas flues 28 of the coke ovens, thence into the main off-gas flue 22 thence past the valve 21 into the regenerator 19 which the said off-gases heat in passing therethrough, thence past the valve 15 into and through the pipe 25 thence into the stack whence said off-gases are discharged into the atmosphere.

In the case of retort ovens of previous types the adjustment of the quantities of combustion gases and the temperature produced thereby in the different heating flues, can only be properly regulated for one direction of the flow of the combustion gases and the off-gases produced thereby, whereas when, in most all of these prior ovens, the direction of the flow of these gases is changed, as in reversing, all the previous

regulations are disarranged, as the intensities of the heat in the different flues is modified and reversed, besides which, the frictional losses, due to the movements of the gases through the said flues is modified on account of the different paths taken by said gases, causing a variation of flow, temperature and heat. On the other hand, by means of my construction, the adjustment and regulation of the combustion gases being once made, is substantially maintained without much change, while the length and arrangement of ducts and flues remains constant, thereby conducing to ease and regularity of operation and maintenance of the ovens, all of which will be readily understood by one skilled in this art.

It will thus be seen that the construction of my oven is distinctive in that the flow of heating gases through the vertical heating flues of the same is always in the same direction, and is easily regulated and controlled by means adapted for this purpose, while the air for combustion of the same is heated by the off-gases by means of the regenerators and is supplied in a heated condition to the fuel gas, the direction of the hot air and that of the off-gases being the only change in these respects which has to be made during the operation of heating the ovens.

Although I have shown blowers such as 12 and 13 for supplying air for combustion, I may dispense with these and operate by stack-draft alone, and although I have shown regenerators of cylindrical form, one at each end of the battery, I may make these of rectangular or other form and disposition, as will be readily understood by those skilled in this art.

Although I have shown and described my invention in considerable detail, I do not wish to be limited to the exact and specific details shown and described, but may use such substitutions, modifications or equivalents thereof, as are embraced within the scope of my invention, or as pointed out in the claims.

Having thus described my invention, what I claim and desire to secure by Letters Patent is:—

1. A coke oven provided with a plurality of heating flues in the side walls thereof, gas and air mixing chambers, means for introducing fuel gas and combustion air into said mixing chambers, regenerator adapted to be alternately connected by main flues with the off-gases and with the combustion air, whereby the latter is heated, air means for reversing the direction of flow of said combustion air and the off-gases in the main flues, while the flow of fuel gas and combustion air is maintained in a constant direction in said heating flues, substantially as described.

2. A coke oven provided with a plurali-

- of heating flues of inverted U-form, gas and air mixing chambers at the lower ends of one of each of the legs thereof, means for introducing fuel-gas and combustion air into said mixing chambers, regenerators adapted to be alternately connected with the off-gases and with the combustion air, whereby the latter is heated, and means for reversing the direction of the flow of said combustion air and off-gases through said regenerators, while the flow of fuel gas and combustion air is maintained in a constant direction through said heating flues.
3. A coke oven provided with mixing chambers and off gas chambers, a plurality of heating flues in the side walls of the oven, longitudinal hot air flues and off-gas flues adapted to be connected with the entrance and exit ends thereof, respectively, main hot air flues and main off-gas flues connecting with the respective longitudinal flues through said mixing chambers and said off gas chambers respectively, regenerators adapted to be connected with said main flues and means for reversing the direction of the flow of the hot air and off-gases through the same, and means for supplying the fuel gas and hot air in constant directions through said heating flues.
4. In a retort oven of the class described, a plurality of double heating flues in the side walls thereof, mixing chambers provided with air and gas supply connected with the up-draft legs of the said flues, off-gas chambers connected with the down-draft legs of said heating flues, a main hot air flue connecting with said mixing chambers, a main off-gas flue connecting with said off-gas chambers, regenerators adapted to be connected with said main hot air and off-gas flues, means for reversing the direction of the flow of the gases in said regenerators and main flues, and means for furnishing a continuous supply of fuel gas to said mixing chambers.
5. In a retort coke oven of the class described, a plurality of double heating flues of inverted U-form in the side walls thereof, mixing chambers connected with the lower ends of one of each pair of legs, a fuel gas
- and hot air supply connected with said mixing chambers, off-gas chambers connected with the down-draft legs of the said heating flues, longitudinal hot air flues connected with said mixing chambers and with a main hot air flue, longitudinal off-gas flues connected with the down-draft legs of said heating flues, and with a main off-gas flue, regenerators adapted to be connected with said main air and off-gas flues, means for reversing the direction of the flow of the gases in said main flues and for maintaining a constant direction of the flow of fuel gas and combustion air through said heating flues.
6. In a coke oven of the class described, provided with a plurality of duplex heating flues in the side walls thereof, means for supplying fuel gas and combustion air to the up-draft legs of each of said flues, means for withdrawing the off-gases from the lower ends of the other legs of said flues, regenerators and main flues connecting with hot air and off-gas ends of said heating flues, and means for reversing the direction of flow in said main flues, the total length of ducts from regenerator to regenerator for said gases being substantially equal.
7. In a coke oven of the class described, a plurality of duplex heating flues in the side walls thereof, a corresponding plurality of fuel gas openings connecting with one leg of each of the said duplex flues with means for regulating the flow of gas there-through, off-gas chambers and flues connecting with the other legs of said duplex heating flues and with a main off-gas flue, a main hot air flue adapted to supply combustion air to said fuel gas, and means for reversing the direction of flow of said combustion air and off-gases in the said main flues, while maintaining the flow of fuel gas and combustion air in a constant direction through said heating flues.

In testimony whereof I hereto affix my signature in the presence of two witnesses.

ARTHUR E. PETERS.
